ELECTRON RAY VOLTAGE INDICATOR

**Keene S. Jackson, Springfield, N. J., assignor, by
mesne assignments, to Radio Corporation of
America, New York, N. Y., a corporation of
Delaware**

Application May 27, 1938, Serial No. 210,335

4 Claims. (Cl. 171—95)

My invention relates to visual voltage or tuning indicators of the electron ray type, particularly to tuning indicators for radio receiving sets.

5 A tuning indicator for radio receivers now in commercial use comprises an electron discharge device with a cathode coaxial with a dish-shaped anode or electron target interiorly coated with fluorescent material which glows when bombarded by electrons. Parallel to the cathode and 10 in the electron path between the cathode and target is an electron ray-controlling electrode connected to a voltage indicative of the resonant condition of the radio receiver. Usually the 15 voltage applied to the ray-control electrode is increased as the radio receiver is tuned to a carrier so that the electron shadow cast by the ray-control electrode on the target closes or reduces to a minimum, and preferably the shadow angle is zero at resonance. Although 20 the voltage applied to the ray-control electrode may be taken from an automatic volume control circuit, the shadow angle, when adjusted to close on strong signals, will not completely close to give accurate tuning indication on weak signals.

25 The object of my invention is a visual tuning indicator which will accurately indicate resonance in a radio receiver for both strong and weak signals.

30 The novel features which I believe to be characteristic of my invention are set forth with particularity in the appended claims but the invention itself will best be understood by reference to the following description taken in connection with the accompanying drawing in which Figures 35 1 and 4 are diagrammatic representations of a tuning indicator tube and circuits embodying my invention, Figure 2 is an end view of the visual indicator tube connected according to my invention, and Figure 3 shows curves explanatory of the operation of my improved tuning indicator.

The electron ray tube shown in Figure 1 and described in detail in the co-pending application of Walter van B. Roberts, Serial No. 198,717, filed 45 March 29, 1938, and assigned to Radio Corporation of America, comprises an envelope 1 enclosing cathode 3 coaxial with a dish-shaped electron target 2 interiorly sensitized with a material which glows when bombarded with electrons. 50 Rod or fin-shaped ray-control electrodes 4 and 5 supported on opposite sides and parallel to the cathode, are adapted to deflect the electrons flowing from the cathode to the target. The potential of ray-control electrodes 4 and 5 with respect to the cathode determines the deflection 55

of electrons and the size of the shadow angles 6 and 7, represented in Figures 2.

Means are provided according to my invention for reducing shadow angle 6 to zero when the level of the received carrier wave is low and for closing shadow angle 7 only when the strength of the received carrier is high. The voltages applied to the ray-control electrodes are obtained respectively from a single source of voltage in the radio receiver proportional to the strength of the received carrier. A common means for deriving a direct current proportional to the strength of the received carrier, shown in Figure 1, comprises a detector 8 in series with a load resistor 9 and the secondary winding 10 of a transformer coupled to the radio or intermediate frequency circuits of the radio receiver. The voltage generated across resistor 9 is applied, according to my invention, directly to the control grid 11 of a screen grid amplifier 12 through a filter resistor 13. This direct current voltage may, if desired, be applied also to the grids of amplifiers in the radio receiver through conductor 14 for automatically controlling the gain in those amplifiers. Anode 15 and screen grid 16 are connected to a high voltage source 17 through resistors 18 and 19.

Space current in amplifier 12 flows to the anode and screen grid respectively through resistors 18 and 19 and produces voltage drops which lower the voltage of ray-control electrodes 4 and 5 with respect to the target. The amount of current flowing through resistor 18 or 19, determined by control grid 11, determines the potential of anodes 15 and 16 and the directly connected ray-control electrodes 4 and 5. Accordingly, the bias on control grid 11, which is proportional to the carrier signal strength, controls the shadow angles 6 and 7. 30 35

The screen grid tube 12 is selected with a 40 so-called remote cut-off in which the plate current reduces to zero only with a high negative control grid bias. I have found that in tubes of the type commercially known as the 6K7, 6U7G or 6D6., the plate current has a sufficiently low 45 value, when the control grid voltage is -24 volts, source 17 is 100 volts, and resistors 18 and 19 are 200,000 ohms each, that the shadow angle 1 approaches zero and that the shadow angle 6, controlled by the screen grid current, approaches 50 zero at about -9 volts control grid bias. The relation of the control grid voltage at 11 and the plate current and the screen grid current, represented by shadow angles 7 and 6 respectively, have been plotted in curves shown in Figure 55

3. It can be seen that both the shadow angles are at a maximum when the control grid voltage is zero. As the control grid voltage is gradually increased in a negative direction, indicative of approach to resonance, the shadow angle 6 rapidly decreases and becomes zero at -9 volts. At this voltage, however, shadow angle 7 has not appreciably changed and closes gradually and becomes zero only at about -24 volts.
- 10 In operation weak signals may be accurately tuned in by observing the closure angle at 6. Upon tuning in strong signals, shadow angle 6 becomes zero and the carrier may be accurately tuned in by observing shadow angle 7. Good results have been obtained by adjusting the values of resistors 18 and 19 to about 200,000 ohms each and the voltage of source 17 to 100 volts when applied to an amplifier of the 6K7 type. The difference between the control grid voltage at which the two shadow angles become zero may be adjusted by changing the ratio of resistance of resistors 18 and 19. If, for example, resistor 19 were increased in value the shadow angle 6 produced by ray-control electrode 5 would close at a higher negative control grid voltage.
- 15 The tuning indicator embodying my invention, shown in Figure 4, comprises means for controlling the potentials of the two ray-control electrodes and for changing said potentials at different rates in response to changes in the control grid voltage of the amplifier. In this embodiment of my invention resistor 20 is connected between the voltage source and the anode of a conventional amplifier 21. The target is connected to the high voltage end of the resistor and the ray control electrodes are tapped to the resistor at spaced points so that the shadow angles produced by ray-control electrodes 4 and 5 may be varied at different rates by the control grid voltage of amplifier 21 as in Figure 1. For a given difference 20 in the control grid voltage at which the two shadow angles close, the relative values of the two portions of resistor 20 may be readily determined. With the left and right hand portions of resistor 20 adjusted to 100,000 and 250,000 ohms each, the shadow angle of ray-control electrode 5 reduces to zero first with a negative grid bias voltage of 16.5 volts, and the shadow angle of ray-control electrode 4 reduces to zero with a grid control bias of -27.5 volts where the amplifier 21 is of the 6K7 type with the suppressor and screen grid being tied to the plate and with a B voltage of about 135 volts.
- 25 The visual tuning indicator constructed according to my invention accurately indicates resonance in a radio receiver whether the level of the received carrier is high or low.

I claim:

1. A visual indicator of variable voltages comprising a cathode, an electron target with a surface facing said cathode which fluoresces with electron bombardment, two ray-control electrodes on opposite sides of said cathode for casting an

electron shadow on said target, means for controlling the potential of one of said ray-control electrodes, means for controlling the potential of the other of said ray-control electrodes, said control means comprising an amplifier for changing 5 said potentials at different rates in response to changes of said variable voltage comprising a cathode, control electrode, screen grid, and anode, said anode and screen grid being separately connected to said ray-control electrodes, resistors 10 connected between said ray-control electrode and target, said control electrode being biased by said variable voltage.

2. A visual indicator of variable voltages comprising a cathode, a target facing said cathode 15 which fluoresces upon electron bombardment, two spaced ray-control electrodes between said cathode and target, means for changing the potentials of said ray-control electrodes with respect to said cathode and target in response to 20 said variable voltages comprising an amplifier with a cathode, control grid, screen grid, and anode, a voltage source connected at one end to the amplifier cathode and connected at the other end to said target and through resistors to said 25 screen grid and anode, the two ray-control electrodes being connected to the resistors at points of different potentials.

3. A visual indicator of variable voltages comprising a cathode, a target facing said cathode 30 which fluoresces upon electron bombardment, two spaced ray-control electrodes between said target and cathode, means for changing the potentials of said ray-control electrodes with respect to said cathode in response to said variable 35 voltages comprising an amplifier with a cathode, control grid, screen grid, and anode, a voltage source connected at one end to the amplifier cathode and connected at the other end through a resistor to said anode, said other end of the 40 voltage source being connected to said screen grid through a second resistor, one ray-control electrode being connected to said anode and the other ray-control electrode being connected to said screen grid, and means for impressing said 45 variable voltages on said control grid.

4. A visual indicator of variable voltages comprising a cathode, a target facing said cathode which fluoresces upon electron bombardment, two spaced ray-control electrodes between said 50 target and cathode, means for changing the potentials of said ray-control electrodes in response to said variable voltages comprising an amplifier with a cathode, control grid, screen grid and anode, a voltage source connected at one end to 55 the amplifier cathode and connected at the other end to said target and through a resistor to said anode, the two ray-control electrodes being connected to spaced points on said resistor, and means for impressing said variable voltages on 60 said control grid.
